UNITED STATES PATENT OFFICE.

FREDERICK SHOLES, OF ST. LOUIS, MISSOURI.

HAND-STAMP.

SPECIFICATION forming part of Letters Patent No. 360,736, dated April 5, 1887.

Application filed November 18, 1886. Serial No. 219,296. (No model.)

To all whom it may concern:

Be it known that I, FREDERICK SHOLES, of St. Louis, Missouri, have made a new and useful Improvement in Hand-Stamps, of which 5 the following is a full, clear, and exact description.

The improvement consists in providing a single handle with a series of stamp or type bearing frames so shaped and arranged and 10 so connected with the handle that any one of them can be turned into position for use and the others of the series meanwhile relatively adjusted to not interfere with its use, substantially as hereinafter described and claimed, 15 and as illustrated in the annexed drawings, making part of this specification, and in which—

Figure 1 is a view in perspective of the improved stamp, all of the stamp-bearing frames being folded into the plane of the handle. Fig. 2 is a view in perspective from another standpoint, and showing one of the stamp-bearing frames upturned to one side of the handle; and Figs. 3, 4, 5 are details.

25 The same letters of reference denote the same parts.

A represents the handle, and B B' B² B³ represent the stamp-bearing frames. The handle is of a familiar shape, and such as to 30 permit of its being readily grasped in the hand. It is provided with a projection or projections to furnish bearings or supports for bearings upon which the stamp-bearing frames may be turned. The most desirable 35 form of such projection is that shown, it being a plate, C, of metal extending along the under side of the handle and suitably secured thereto, and at its ends turned down to form the ears c c', in which is held the rod c'. The 40 stamp-bearing frames depend from and are adapted to be swung upon the rod c'. They diminish in size, enabling them to be folded successively within each other, as shown in Fig. 1; or any one or more of them, as indicated by the position of the frame B, Fig. 2, 45 may be swung aside to permit the lowest remaining frame (the frame B', as shown in Fig. 2) to be brought into use, for the advantage accruing from the improved device is that it permits several differently worded or 50 designed stamps to be attached to the same handle, and in such manner that any desired one

of them can be readily used and as readily displaced and another brought into use, and thus in effect provide several stamps nearly, 55 if not quite, within the compass of a single stamp as hitherto constructed.

An auxiliary feature of the stamp is the means for steadyng the frames in their two positions, but so as to permit of their being 60 readily adjusted. This is effected, preferably, in the following manner: D represents a spring attached at d to the handle A, and at its end d' adapted to press upon the ends b of the frames when the frames are turned into 65 the plane of the handle and upon the side b' of the frames when they are swung aside. One, c², of the ears, where the rod c' is held, is slotted vertically, substantially as shown at c³, thereby permitting that end of the rod and 70 frames to be moved the length of the slot toward and from the handle. The ends b are notched at b², Figs. 1, 2, 3, to engage with a pin, E, that projects from the ear c². As long as the stamp is not being impressed in a downward direction, the rod c', by reason of the 75 gravity of the frames or the action of the spring D, or both the gravity and the spring action, drops in the slot c³, and the notched ends b of the frames are disengaged from the 80 pin E, and the frames are free to be swung upon the rod c' to and from the positions shown, respectively, in Figs. 1 and 2; but when the stamp is impressed upon a surface, 85 as when used, the action of the spring and the weight of the parts are overcome and the rod c' is moved upward in the slot c³, and the notched ends b brought into engagement with the pin E, whereupon the frames B, &c., become locked and remain fastened in an up- 90 right position until the downward pressure upon the stamp is released.

The type F upon the frames B B', &c., may be of rubber or any suitable material, and it may be secured to or incorporated in the 95 frame, as desired, so that when the frame is turned down the type is in position for being stamped upon the surface being printed upon; and in the place of a type a die may be used.

I desire not to be confined to the special form of type-bearing frame shown.

I claim—

1. A stamp consisting of a single handle

and a nest of stamp-bearing frames, said frames being pivoted independently of each other to said handle, as and for the purpose of enabling any one of the frames to be brought 5 into use.

2. The combination of the handle, the pivoted stamp-bearing frames diminishing in size, and the spring, substantially as described.

3. The combination of the handle A, the 10 nest of stamp-bearing frames B B', &c., the

ear c, the ear c', slotted at c', the rod c', and the pin E, substantially as described.

4. The combination of the handle A, the nest of stamp-bearing frames B B', &c., the ear c, the slotted ear c', the rod c', the spring 15 D, and the pin E, substantially as described.

FREDERICK SHOLES.
